UNITED STATES PATENT OFFICE.

HARVEY M. LEWIS, OF BUFFALO, NEW YORK.

PUZZLE.

1,287,709.

Specification of Letters Patent. Patented Dec. 17, 1918.

Application filed February 9, 1918. Serial No. 216,248.

To all whom it may concern:

Be it known that I, HARVEY M. LEWIS, a citizen of the United States, residing at Buffalo, in the county of Erie and State of

5 New York, have invented certain new and useful Improvements in Puzzles, of which the following is a specification, reference being had to the accompanying drawings.

This invention relates to an improved 10 puzzle, and has for its primary object to provide a simple and amusing puzzle which will require considerable patience in the solving thereof.

It is another object of my invention to 15 provide a puzzle device which can be manufactured at relatively small cost, and can therefore be distributed as an advertising novelty.

It is a further general object of the invention to provide a puzzle embodying a 20 puzzle board having a field delineated thereon and spaced perforations extending through said field and additional perforations or openings outside of the field, and a 25 member having spaced prongs adapted to be manipulated in the openings to finally position one of the prongs through a central objective opening.

With the above and other objects in view 30 the invention consists in the improved construction and arrangement of the several features of the device as will be hereinafter more fully described, subsequently claimed and illustrated in the accompanying drawing, 35 wherein:—

Figure 1 is a plan view of the puzzle board; and

Fig. 2 is a perspective view of the member used in solving the puzzle.

40 Referring in detail to the drawing, 5 designates the puzzle board which is preferably in the form of a sheet of stiff card board. On this card board sheet, a cross indicated at 6 is outlined, and the field within 45 the outlines of this cross may be colored red, in simulation of the emblem of the Red Cross Society. Along the border or edge of the cross and within the field defined thereby, a multiplicity of spaced openings 50 7 are formed through the card board sheet and in addition thereto a central objective opening 8 of the same size as the openings 7 is provided. In spaced relation to the upper end of the upwardly projecting arm 55 of the cross, a relatively large opening 9 is formed through the card board sheet and

above this arm of the cross exteriorly thereof additional small openings 10 of the same size as the openings 7 are formed in the puzzle board.

60 It is to be understood, however, that the board need not necessarily be provided with openings extending entirely therethrough, but sockets or recesses may likewise be used, and it is to be understood that the word "re- 65 cesses" as employed in certain of the claims, is to be construed broadly as defining both a perforation or opening, and a socket, indentation, or depression, which is closed at 70 one end.

11 designates the member which is used in solving the puzzle, and in the illustrated embodiment of the invention, this member consists of a length of wire twisted upon 75 itself to provide a handle portion 12, the ends of the wire being extended in opposite directions from the handle and terminating in the angularly projecting points or spurs 13.

In solving the puzzle, it is the purpose of 80 the would be solver to position one of the spurs or points 13 of the member 11 in the central objective opening 8 by proceeding step by step over the perforated field of the 85 puzzle board, engaging the points 13 of the member 11 in the spaced openings. The start may be made from any place upon the perforated field, and it will quite frequently occur that the would-be solver of the puzzle 90 will find his progress stopped by his inability to engage one of the points 13 in any one of the perforations or openings, without removing the other point from the opening in which it is engaged. The openings 7 are of course definitely and precisely 95 arranged and there is no possible way in which the objective opening 8 may be reached simply by engaging the points 13 only in the openings 7 within the field of the cross. It is necessary that the operator 100 shall proceed so that one of the points 13 may be engaged in the large opening 9, and in order to do this, he must first proceed so that the points will be engaged in certain of the openings 10 above the cross. Thus as 105 the operator proceeds and finally locates one of the points 13 in the opening designated 10^a, he can then engage the other point 13 in the large opening 9, and from this large opening, the points 13 may be engaged in 110 other of the openings 7 in the central portion of the field until one of the points is

finally engaged in the central opening 8. The average person, would consider the larger opening 9 as means for hanging the puzzle board upon a nail, and that the 5 points of the member 11 were to be engaged only in the smaller openings 7 and 10. After one of the points 13 has been engaged in the opening 9, the other point 13 can only be engaged in the opening 7^a, and the openings 7 are so spaced that it is impossible to engage one of the points 13 in this opening 7^a before engaging said points in the openings 10 above the upper end of the cross. Thus it will be seen that there is only one 10 possible way of solving the puzzle and it will require considerable thought, patience and ingenuity on the part of the would-be solver before he will be successful in engaging one of the points 13 in the objective 15 opening 8.

It will thus be seen that I have devised a very simple, interesting and amusing puzzle and one which can be produced in large quantities at very small manufacturing cost. The puzzle is primarily designed for the purpose of creating interest in the work of the Red Cross Society and in aiding the collection of finances, as an aid to the activities of said society. However, it 20 is manifest that my improved puzzle may be adopted by other organizations or manufacturers, and instead of arranging the perforated field in the form of a cross, this field of perforations may be of various other 25 shapes. It is also to be understood that it is not necessary to provide a member 11 of the identical form herein referred to and shown in the drawing, as this member used in solving the puzzle may be otherwise constructed of wood, card board or other 30 materials than wire. It is therefore to be understood that while I have herein shown and described the preferred construction and arrangement of the several features of 35 the device, the same is nevertheless susceptible of considerable modifications therein, and I therefore reserve the privilege of 40 45

adopting all such legitimate changes as may be fairly embodied within the spirit and scope of the invention as claimed. 50

Having thus fully described my invention, what I claim is:

1. In a puzzle, a puzzle board having a field delineated thereon, and a multiplicity of spaced openings extending through said field and an additional objective opening, 55 said puzzle board being also provided with an additional relatively large opening within the field, and a member having spaced points adapted for engagement through the first named openings by a step by step movement whereby one of the points may be engaged in said larger opening, said points being subsequently engaged through certain of the smaller openings, and one of 60 65 said points finally engaged in the objective opening.

2. In a puzzle, a puzzle board having a field delineated thereon in the form of a cross and a multiplicity of spaced openings 70 extending through said field and an additional central objective opening, said puzzle board being also provided beyond the end of one arm of the cross with additional spaced openings therein, all of said openings being of uniform size and said board having a single relatively large opening therein located adjacent the end of one arm of the cross, and a member having spaced points adapted for engagement through the 75 first and second named openings by a step by step movement to position one of the points in said larger openings, said points being then subsequently engaged through certain of the first named openings and one 80 85 of the points finally positioned in the central objective opening.

In testimony whereof I hereunto affix my signature in the presence of two witnesses.

HARVEY M. LEWIS.
